VENETIAN BLIND SLAT

Oscar L. Engstrom, New York, N. Y.

Application February 16, 1939, Serial No. 256,759

6 Claims. (Cl. 156—17)

This invention relates to window coverings, and more particularly to an improved slat for a Venetian blind.

One object of this invention is to provide a Venetian blind slat which is constructed of thin sheet metal strips, spaced apart and stiffened by a thin metallic filler member which is adapted to permit ventilation through the slat.

A further object is to produce a Venetian blind slat which will be relatively inexpensive to manufacture, simple in construction, compact, ornamental in appearance, easy to clean, noiseless, light in weight, fire-proof, which will not curl or warp, and very efficient and durable in use.

With these and other objects in view, which will appear as the description proceeds, there have been illustrated in the accompanying drawings, several forms in which the invention may be conveniently embodied in practice.

20 In the drawings:

Fig. 1 is a perspective view of part of a Venetian blind embodying the invention.

Fig. 2 is an enlarged cross-sectional view of one of the improved slats, showing the first form of filler member.

Fig. 3 is a perspective view of the improved slat, showing the parts thereof in separated relationship prior to assembly.

Fig. 4 is a detail perspective view on a larger scale of a rubber end cap for the slats.

Fig. 5 is a broken enlarged detail view, showing a slat having a modified second form of filler member.

Fig. 6 is a broken detail view of a slat, showing a modified third form of filler member.

Fig. 7 is a broken detail view, showing a modified fourth form of filler member.

Figs. 8, 9 and 10 are broken detail views of a modified fifth form of filler member.

Fig. 11 shows a modified sixth form of filler member.

Figs. 12 and 13 show slats having two other modified forms of filler members.

Figs. 14 and 15 show two additional modified forms of slats wherein no filler members are used.

Referring now to the drawings wherein like reference characters designate like parts throughout the several views, Fig. 1 discloses the general appearance of part of a Venetian blind embodying the principles and features of this invention, which comprises a plurality of horizontal slats 10, spaced apart and connected in the conventional manner by pairs of fabric strips 11 and 12, said slats being adapted to be raised and

lowered, as well as opened and closed, by said strips and said central cord 13 in the usual manner.

Referring now to the first form of slat shown in Figs. 2 and 3, the numeral 14 denotes a flat metallic upper strip of sheet metal adapted to form one face portion of the slat, and the numeral 15 indicates a second metallic lower strip of sheet metal adapted to form the other face portion of the slat. The lower strip 15 is offset 10 upwardly at its ends to form vertical sides 16 and 17 and outwardly extending horizontal side edges 18 and 19, which are adapted to abut against the under surface of the strip 14 and be formed therewith into double lock seams 20 and 21. 15

In order to stiffen and reinforce the slat, provision is made of an elongated filler member 22, formed of sheet metal, having lengthwise corrugations 23 extending the full width of said slat, and said filler piece 22 being disposed between the parallel 20 upper and lower strips 14 and 15 for holding said strips 14 and 15 spaced apart. The corrugations 23 in the filler member 22 are formed with relatively sharp angled V-shaped corners 24, connected by flat alternately inclined portions 25. 25

At the center of each slat provision is made of an elongated hollow eyelet 26 preferably of metal, extending through the strips 14 and 15 of the slat 10 and the corrugated filler piece 22 with its long axis crosswise of said slat to provide a 30 smooth passageway therethrough for the cord 13. The eyelet 26 has upper and lower flanges 27 and 28 which overlie the upper and lower strips 14 and 15 respectively.

At each end of the slat provision is made of a 35 protective noise-preventing and shock absorbing end cap 29, preferably of rubber, although metal or molded composition may be substituted if desired. Each end cap 29 has an upper face 30 and a lower face 31 which extend inwardly a short 40 distance over the end of the slat. The cap 29 also has an end face 32 provided with an elongated opening 33 to permit the circulation of air through the corrugations 23 which extend throughout the length of the slat. As will be 45 clear from Figs. 1, 2 and 4, the end face 32 of each cap acts as a retaining means for the filler piece 22 to prevent it from sliding out of position.

In the modified slat construction illustrated in 50 Figs. 5, a filler piece 35 similar to that shown in Figs. 1 to 4 is shown, but it has its side edge portions 36 integral with and extending beyond the corrugated portion 37 thereof, which side edges 36 are interlocked with the side edges of the 55

upper and lower slat strips 14 and 15 when the latter are connected by double lock seams 38.

In the modified third form of filler member 40 shown in Fig. 6, the corrugations 41 are provided with rounded (instead of V-shaped) corners 42, which abut the upper and lower strips 14 and 15 and are connected by flat inclined portions 43.

The modified fourth form of filler member 44 shown in Fig. 7 is provided with arch-shaped 10 corrugations 45 which have flat portions 46 abutting the upper and lower strips 14 and 15. The flat portions 46 are joined together by inclined portions 47.

In the modified fifth form shown in Figs. 8, 9 15 and 10, the filler 48 is formed from a flat strip of sheet metal 49 having staggered elongated cup-shaped protuberances 50 struck up from one face thereof. The filler piece 48 may be assembled in the slat 10 by placing its flat top 20 face 51 so that it will abut the upper strip 14, with the protuberances 50 abutting the lower strip portion 15, whereby the air passage 52 through the slat will not be straight but will be interrupted and serpentine in form, as indicated by dotted lines in Fig. 9.

The sixth form of filler piece 53 shown in Fig. 11 is similar to that shown in Figs. 8, 9 and 10, but instead of forming the protuberances all on one side of the strip 49, protuberances 54 and 30 55 are alternately struck up, first from one side of a strip 56, and then from the other side. When assembled between the upper and lower strip portions 14 and 15 of a slat 10, the tops of the alternately directed protuberances 54 and 55 35 will abut against both of said strip portions 14 and 15, and will hold said strip 56 disposed in an intermediate position therebetween, whereby two serpentine insulating air passages 57 and 58 will be provided for the slat 10, one on either 40 side of the strip 56.

One advantage of the present improved Venetian blind slat is that it cannot split, and hence, replacement or repairs will seldom be required. Moreover, the provision of the reinforcing filler members will not only maintain the slat strips 45 14 and 15 in spaced relation and prevent twisting of the slat and provide for ventilation thereof, but also will provide an insulating air space when in closed position, whereby the blind will effectively act as an insulating medium. Furthermore, the provision in the slat 10 of the 50 double lock seams 20 and 21 along its edges stiffens the slat lengthwise against bending stresses.

The modified form of filler members of the slats illustrated in Figs. 12 and 13 are similar to those shown in Figs. 2, 6 and 7, but instead of having the corrugations extending the full width of the filler member, a flat uncorrugated center portion 59 is provided in the filler member 60 shown in Fig. 12, and a pair of uncorrugated side edge portions 61 are provided in the 60 filler member 62 shown in Fig. 13.

The modified forms of slats shown in Figs. 65 14 and 15 require no filler members whatsoever. In the form shown in Fig. 14, a pair of opposed inwardly directed grooved ribs 63 and 64 are formed in the upper and lower members 65 and 66 of the slat. The ribs 63 and 64 abut each other intermediate the members 65 and 70 66, reinforce the slat, and hold the middle portions thereof properly spaced apart.

In the modified form shown in Fig. 15, a pair of inwardly directed spaced-apart ribs 67 and 68 are formed on one of the side members of the slat and are extended across the slat to engage the other side member thereof. 5

In both of the forms shown in Figs. 14 and 15, the ribs 63 and 64 and the ribs 67 and 68 are held in abutting relation against the opposite side member of the slat, respectively, by the clamping action of the elongated center eyelets 26. 10

While there have been disclosed in this specification several forms in which the invention may be embodied, it is to be understood that these forms are shown for the purpose of illustration only, and that the invention is not to be limited to the specific disclosures, but may be embodied in various other forms without departing from its spirit. It will be further understood that each and every novel feature and combination present in or possessed by the device herein disclosed forms a part of the invention included in this application. 15

Having thus fully described the invention, what is claimed as new and for which it is desired to secure Letters Patent, is:

1. A slat for Venetian blinds comprising spaced apart flat face portions, and a metal longitudinally corrugated filler piece disposed between said face portions to retain them in spaced apart relation and to form ventilating air passages therebetween, the corrugations in said filler piece running the entire length thereof. 30

2. In a slat for a Venetian blind comprising spaced-apart flat upper and lower metallic face portions, a longitudinally corrugated metallic stiffening filler piece disposed between said face portions to retain them in spaced-apart relation and form insulating air spaces therebetween, and rubber silencing caps over each end of said 40 slats, each cap having an opening in its base for admitting air to ventilate said air spaces. 35

3. An all-metal slat for a Venetian blind comprising a pair of spaced-apart flat upper and lower metallic face portions, a metallic stiffener 45 strip disposed between said face portions, said strip having a plurality of nubs struck up therefrom for engaging said face portions to retain them in spaced-apart relation.

4. An all-metal slat for a Venetian blind comprising a pair of spaced-apart flat upper and lower metallic face portions, a metallic stiffener strip disposed between said face portions, said strip having a plurality of nubs struck up from both sides thereof for engaging said face portions 50 to retain them in spaced-apart relation. 55

5. A slat for Venetian blinds comprising spaced-apart flat face portions, and a metal longitudinally corrugated filler piece disposed between said face portions to retain them in spaced-apart relation and to form ventilating air passages therebetween, the corrugation of said filler piece being interrupted to provide a smooth section for reducing the amount of metal required. 60

6. A hollow slat for Venetian blinds comprising a pair of connected spaced-apart flat parallel face strips, and longitudinally corrugated means between said strips to maintain the spacing thereof and provide ventilation therebetween. 65
